NAIL POLISH PROTECTOR

Ruth Sims Carmichael, Davis, Okla.

Application October 4, 1939, Serial No. 297,939

7 Claims. (Cl. 132—73)

This invention relates to manicuring devices and more particularly to a finger support or protector for preventing smearing of nail polish or dressing after applying the same to the finger 5 nails.

The object of the invention is to provide a finger support or protector of simple and inexpensive construction adapted to hold the fingers of the hand in spaced relation to each other after 10 polish has been applied to the finger nails and until the polish has become thoroughly dry or set, thereby to prevent accidental smearing of the polish and insuring a smooth lustrous finish to the finger nails.

15 A further object of the invention is to provide a finger rest or support which will prevent the fingers from coming in contact with each other without tiring effort on the hand and finger muscles and which may be used with equally good 20 results in private homes or by beauticians and others in beauty parlors and the like.

A further object is to provide the finger rest or protector with a pivoted latch for retaining the fingers within suitable receiving sockets 25 while the nail polish is drying, said latch being provided with a longitudinal slot to accommodate any rings that may be worn on the fingers when applying polish to the nails and thus prevent the latch from exerting pressure on the rings when 30 said latch is moved to closed position.

A still further object of the invention is generally to improve this class of devices so as to increase their utility, durability and efficiency.

35 In the accompanying drawing forming a part of this specification and in which similar numerals of reference indicate corresponding parts in all the figures of the drawing:

Figure 1 is a top plan view showing the manner of using my improved finger support or protector,

Figure 2 is a perspective view showing the latch in closed position,

Figure 3 is a similar view showing the latch in open position,

Figure 4 is a transverse sectional view taken on the line 4—4 of Figure 3, and

Figure 5 is a perspective view illustrating a modified form of the invention.

50 The improved protector forming the subject-matter of the present invention comprises a rest or support including a body portion 5 formed of wood, rubber, cork, Cellophane or other suitable material, said body portion having a flat base 55 6 adapted to rest on a table or other support and

having its front wall preferably concave and its rear wall convex, as shown.

Formed in the top of the body portion 5 are a plurality of converging finger-receiving seats or sockets 7 opening through the front and rear walls of the body portion and separated by intermediate partitions 8 so as to prevent the fingers of the hand from coming in contact with each other while the polish or dressing on the finger nails is drying. The walls of the sockets 7 diverge 10 in the direction of the rear wall of the body portion 5 so that, when the hand is supported on said body portion, the fingers of the hand will be separated in simulation of a fan and thus prevent the fingers from coming in contact with 15 each other and smearing the polish or dressing applied to the finger nails.

Pivotal mounted at 9 on one end of the body portion 5 is a latch 10 preferably formed of co-acting relatively thin rods or wires spaced apart 20 to form an intermediate slot 11 so as to accommodate any rings that may be worn on the fingers at the time the polish is applied to the finger nails and thus prevent the latch from exerting an inward pressure on the rings and hurting 25 the fingers when the latch is moved to closed position. The free end of the latch 10 is provided with an angular portion 12 adapted to engage a resilient keeper 13 secured to the adjacent end of the body portion 5 to retain the finger 30 nails in the sockets 7 while the polish on the finger nails is drying.

In operation, the polish or dressing is applied to the finger nails with a brush in the usual manner and after the finger nails have been 35 coated with the polish the fingers are inserted within the sockets 7 and the latch 10 swung to closed position in engagement with the keeper 13. When the hand is placed on the rest or support in the manner just described, the tips of the fingers will be separated so that there is no liability of the fingers contacting with each other and smearing the polish while the polish is drying and all tendency to fold the fingers inwardly to a natural position is resisted by the walls of 45 the sockets 7 and the latch 10.

Ordinarily, when polish is applied to the finger nails, it is necessary to wait approximately five to twenty minutes for the polish to thoroughly dry and during this interval care must be exercised to prevent the fingers from coming in contact with each other or with extraneous objects which would tend to smear the polish. This period of waiting with the fingers separated is very tiresome and trying as the natural tendency is 55

to permit the fingers to assume their normal position with the result that the polish deposited on the fingers becomes smeared, as previously stated. The present device provides a means for supporting the fingers of a hand in spaced relation while the polish on the finger nails is drying, and owing to the fact that the fingers are locked within the sockets by means of the latch 10 any tendency to bring the fingers together or fold them in the direction of the palm of the hand is effectually prevented. Moreover, the device provides a convenient and comfortable rest for the fingers during the drying of the nail polish without tiring effort on the hand and finger muscles so that the application of the polish becomes a pleasure instead of an ordeal. After the polish has become thoroughly dry or hard on the finger nails of one hand, the latch 10 is moved to open position and the fingers withdrawn from the sockets 7 after which the fingers of the other hand may be inserted in the sockets 7 to effect drying of the polish on the nails of that hand.

If desired, however, the protectors may be made in pairs so that, while the nail polish is drying on one hand, the other hand can be inserted in a companion protector and polish applied to the finger nails, thus reducing the time required on the part of both the operator and the person whose nails are being polished.

In Figure 5 of the drawing, there is illustrated a modified form of the invention, in which the body portion 5' is constructed of relatively hard rubber or any other desired material while the upper portion thereof is elastic. In this form of the device, the elastic material at the side walls of the finger-receiving sockets is curved inwardly to form overhanging resilient retaining lips 14 having their inner longitudinal edges spaced apart to permit the insertion and removal of the fingers. These lips 14 by engagement with the fingers serve to prevent accidental displacement thereof while the polish is drying on the finger nails, thus dispensing with the latch shown in Figure 1 of the drawing. As the retaining lips 14 are flexible, they will likewise accommodate any rings on the fingers and prevent inward pressure thereon.

It will, of course, be understood that the protectors may be made in different sizes and shapes and constructed of any suitable material without departing from the spirit of the invention.

Having thus described the invention, what is claimed as new is:

1. A device of the class described comprising a hand support having spaced sockets formed

therein and adapted to receive the fingers of a hand, and a ring-receiving device mounted on the support and adapted to extend across the fingers at said sockets for retaining the fingers therein.

2. A device of the class described comprising a hand support having a flat base and provided with a concave front wall and convex rear wall, there being spaced finger-receiving sockets extending transversely of the support and intersecting the concave and convex walls thereof, and a securing latch mounted for swinging movement on said hand support and provided with a ring-receiving slot.

3. A device of the class described comprising a concavo-convex hand support having spaced finger-receiving sockets opening through the top thereof and defining intermediate tapered partitions, a latch pivotally mounted on one end of the support and extending over said sockets, and a keeper mounted on the other end of the support for engagement with said latch.

4. A device of the class comprising a hand support having spaced radiating finger-receiving sockets formed therein and opening through the top and front and rear walls thereof and defining intermediate partitions, and a ring-receiving member extending across the upper open ends of the sockets for retaining the fingers therein.

5. A device of the class described comprising a hand support having spaced finger-receiving sockets formed therein, and a latch mounted on the support and extending across said sockets, said latch being provided with a longitudinally disposed ring-receiving slot.

6. A device of the class described comprising a hand support having spaced finger-receiving sockets formed therein and defining intermediate tapered partitions, a keeper secured to one end of the support, and a latch mounted on the other end of the support for detachable engagement with said keeper, said latch comprising co-acting rods spaced apart to form an intermediate ring-receiving slot.

7. A device of the class described comprising a hand support having spaced finger-receiving sockets formed in the top thereof and defining intermediate partitions, the walls of which diverge in the direction of the rear portion of the support, a keeper secured to one end of said support, and a latch pivotally mounted on the other end of the support for engagement with said keeper and having an upwardly bowed intermediate slotted portion.
